Primary Examiner — Garth Rademaker*Assistant Examiner* — Melanie Pellegrini(57) **CLAIM**

The ornamental design for a counting bracelet, as shown and described.

DESCRIPTION

FIG. 1 is a perspective top view of a counting bracelet; FIG. 2 is a front elevation view of the counting bracelet; FIG. 3 is a rear elevation view of the counting bracelet; FIG. 4 is a left side elevation view of the counting bracelet, the right side elevation view being a mirror image thereof; FIG. 5 is a top plan view of the counting bracelet; FIG. 6 is a bottom plan view of the counting bracelet; and, FIG. 7 is a perspective view of the counting bracelet, shown on a user's wrist.

The broken lines shown in FIG. 7 represent environment which forms no part of the claimed design.
